UNITED STATES PATENT OFFICE.

JAMES C. COVERT, OF WATERVLIET, NEW YORK.

DESIGN FOR A HOOK-CASTING.

SPECIFICATION forming part of Design No. 26,540, dated January 19, 1897.

Application filed December 17, 1896. Serial No. 616,074. Term of patent 14 years.

To all whom it may concern:

Be it known that I, JAMES C. COVERT, a citizen of the United States, residing at Watervliet, (formerly West Troy,) in the county of 5 Albany and State of New York, have invented and produced a new and original Design for a Hook-Casting; and I do hereby declare the following to be a full, clear, and exact description of the same, reference being had to the accompanying drawings, forming a part thereof.

This invention relates to an original design for a hook-casting, and is embodied in the construction hereinafter described, and shown in the accompanying drawings, which form a 15 part of this specification.

In the drawings, Figure 1 is an elevation of the casting embodying the design, and Fig. 2 is a plan view of the same.

The casting comprising the design consists 20 in the barrel or body portion A, having the side flanges or wings a and the slightly-tapered rear B. The portion B is curved downward and laterally upward in a compound curve, forming an open eye C. The upper 25 end section of the eye is located, as shown, laterally beyond the plane of the side of the body portion, and the same terminates at a point substantially in line with a protruding or flat-faced lug D on the end of the 30 section B.

E designates the hook-section, which is

looped downward and outward, the end or point section being bent upward and laterally outward in a substantially oblique direction.

The point of the hook terminates on a plane 35 substantially that of the upper surface of the barrel, and the inclination of the point-section is in a direction opposite to that of the eye-section. Such, however, is not essential, as the eye may be bent in the opposite direction, as shown in dotted lines, Fig. 2. The hook may also be bent in the opposite direction, as shown in dotted lines, Fig. 2.

The essential features of the design are the casting formed with the laterally-bent eye 45 and hook sections and the winged or flanged body-section.

The size and length of the portion B may obviously be varied without departing from the general features of the design.

Having thus described the new and original design, what is claimed, and desired to be secured by Letters Patent, is—

The design for a hook-casting, substantially 50 as shown and described.

In testimony whereof I affix my signature in presence of two witnesses.

JAMES C. COVERT.
